UNITED STATES PATENT OFFICE.

HUGH GELLROY BUCHAN, OF WOODBRIDGE, NEW JERSEY.

INDEX.

1,294,043.

Specification of Letters Patent. Patented Feb. 11, 1919.

Application filed February 21, 1913. Serial No. 749,767.

To all whom it may concern:

Be it known that I, HUGH GELLROY BUCHAN, of Woodbridge, in the county of Middlesex and State of New Jersey, have invented certain new and useful Improvements in Indexes, of which the following is a specification.

In certain kinds of indexes, and especially in numerical indexes, in which the indicating letters or numerals, or combinations thereof, are large in number, and especially where they run far into hundreds or thousands, it is frequently extremely desirable that the required indicating number, etc., should be quickly and easily found; that the sheets, cards or leaves making up such index should be so secured together as to be incapable of being tampered with by unauthorized persons, and sometimes it is also extremely necessary and desirable that frequent changes should be made in the index by the insertion of new sheets, cards or leaves at frequent intervals, either for the purpose of changing old entries therein or by insertion of new and additional sheets, cards or leaves. This is especially true of the loose leaf books used by telephone operators in exchanges in large cities for the purpose of looking up changes in the indicating telephone numbers of subscribers.

In such use, in the telephone exchanges, it is absolutely necessary that the index should be in the form of a bound book of small size, close to the operator's hand, and in its use it is essential that any required number among many thousands should be found almost instantaneously.

In the books at present and formerly in use great difficulty has been heretofore experienced in the practical use of these indexes, for the reason that in such bound books, (which of necessity must be of comparatively small size in order to facilitate their use), only about thirty or so cardinal indicating numbers are on constant view, and beyond such first series of the first thirty or so numbers, the succeeding numbers of the thumb-index necessary to be used therein are normally hidden by the sheets of the first series of numbers. The object of my invention is to provide an index composed of a plurality of cards, leaves or sheets, which may be secured together against any unauthorized removal, but all of which may have the indicating letters or

numerals, or combinations thereof, at least those of the cardinal variety, of the entire index proper, brought instantaneously into the view of the user by a simple movement of the hand, the manner of securing the leaves or sheets together being such that elision or multiplication of the separate sheets or leaves may be easily and quickly made by those authorized to make such changes.

My said invention is fully shown and described in the following specification, of which the accompanying drawings form a part, wherein similar letters or numerals of reference designate like or equivalent parts wherever found throughout the several views, and in which:

Figure 1 is a perspective view of my improved index book and binder, taken from the front and bottom, the front cover-leaf being thrown fully back into the open position so as to bring all the cardinal indicating characters on the thumb-tabs of the individual sections of such index simultaneously to view; and in order to more clearly show and bring out the details of construction of certain portions of the device, the same are shown in section.

Fig. 2 is a front view in detail of the back-plate with the U shaped hinged securing-bars in position therein, as the same appears when removed from the cover.

Fig. 3 is a view of the construction shown in Fig. 2, taken in cross-section on the line a—a, and

Fig. 4 is a side view in detail of one of the U shaped securing-bars, the point at which the same appears in cross-section in Fig. 3 being indicated by the dotted line.

Fig. 5 is an end view in cross-section of the rear portion of my improved binder, of a slightly modified form of construction from the one shown in Figs. 1 to 4 inclusive, in the open position.

Fig. 6 is an end view of such modified construction shown in Fig. 5, in the closed position.

Fig. 7 is an end view in cross-section, and in the closed position, of the rear portion of another modified form of construction of my improved index binder from the two shown in Figs. 1 to 6 inclusive; and

Fig. 8 is a front view partially in section of the binder-bar used in the form of binder shown in Fig. 7.

Referring to the drawings:—

As shown in Figs. 1 to 4 inclusive, in the form especially adapted for use as such telephone exchange indexes, my invention consists in substances of a rigid metallic back-plate 1, usually in the form shown in Figs. 2 and 3, of brass, white metal, steel nickel-plated, or other suitable material. This back-plate 1 is usually and preferably of the contour and form shown in Fig. 2, and has been subjected to a punching and swaging or pressing action of a suitable die, in such manner as to swage up therefrom, at the proper points, hinge-sections 2, usually four in number, between and at the end of which are perforations 6' struck out from such plate, into which fit the co-acting securing hinge-sections 3 and 3', (Fig. 4) of the double-walled securing-bars 4, shown in detail and side-view in Fig. 4, which are struck up into practically U shape form from any suitable thin sheet metal, usually steel; such sections 3 and 3' being swaged down so as to be much narrower than the central hollow of the main portion of the securing-bars; and such securing-bars 4 are held in position in the back-plate 1 by suitable hinge-rods 5, passing through the hinge-sections 2 of the back-plate, and through the co-acting hinge-sections 3 and 3' of the securing-bars, as shown in Fig. 1.

The cover C of the bound-book to be formed is usually of flexible leather or some such fabric, formed in one piece, and, in order to prevent turning up of same at the corners or at the front, where it is handled in quick usage, the pocket 6, usually formed by either turning over the edge, or sewing an additional strip on one side thereof, if formed thereon, or therein, within which is placed a stiffening strip of thin metal, usually sheet brass or steel 7, or such strip may be otherwise held in position in any other desired manner. In Fig. 1, the interior fold of the fabric strip is slightly broken away in order to more clearly show the metallic stiffening strip 7, and its relative position.

As shown in Fig. 1, in one of the many forms in which my invention may be embodied, a securing-strip of leather, canvas or other flexible fabric 10, which may be a single piece extending across what is to be the back of the binding C; or instead of a single strip piece, this may consist of two strips 10', as shown in Fig. 5. In either case the strip or strips may be secured to the back C in any desired manner, usually by stitches, as shown at 42, adjacent to the edges thereof. Once the securing-strips 10 or 10' are in position, the back-plate 1 is then superposed upon said strip or strips, and the edges of the securing strip or strips, folded up, inward and over the longitudinal

side edges of the back-plate; and substantially U shaped securing-clips 11 are then slipped over both strip, fabric-fold and back-plate, and firmly swaged down thereon, so that such flexible securing-strip or strips will be firmly secured to the back-plate 1, and all to the binding back-cover C.

In some cases and for certain purposes, it may be desirable to render the back-plate 1 easily removable from the binder-back C. In such cases, instead of the arrangement just described, I prefer to use the modified form of construction shown in Fig. 5, wherein the back-plate 1 is provided at its longitudinal edges with the longitudinal grooves 41; and the securing-strip is as before stated divided into two side parts, and is secured in position by lines of stitches 42, or in any other desired manner. The securing-strips 10' are coiled as shown, and slipped into the central hollow of the substantially cylindrical securing-clip 11', formed of resilient spring metal, and the back-plate 1 is then slid up into the position shown in Fig. 5, so as to bind the loop, and free ends, of the securing-strips by the natural resiliency of the securing-strips 11'.

The form of clip *per se*, as shown, forms no part of the invention herein disclosed, save in combination, but is broadly shown, described and claimed in my United States Letters Patent No. 984,120, granted to me February 14, 1911, and as used herein is a modification of the use thereof, from that shown in such Letters Patent referred to.

Passing through perforations 13 in the walls of the U shaped securing-bars 4, located a short distance from the ends of such bars, are hollow securing-studs 14, each provided with a slotted head 12 to receive a screw-driver, into the hollow female threaded cavity of which fits the like headed male screw 11.

Each sheet, or small plurality of sheets, of the index is provided with a thumb index tab 15 (Fig. 1) usually formed by an integral extension thereof, and covered to prevent wear on both sides, with a thin transparent sheet of celluloid, not shown. These thumb-indexes are arranged in the well-known manner, to facilitate the opening of the book at the proper place, and are numbered or lettered consecutively in the manner appropriate to that particular form of index.

The particular embodiment of my invention shown and described, herein, is in the shape of a loose-leaf bound book carrying a numerical index of a thumb-tab form, each sheet being provided with one of such tabs, but I do not limit myself to such exact form. This particular form, while not limited thereto, is more especially designed and adapted for use in telephone exchanges; and by such use an operator can instantaneously

find any subscriber's present number up to an exceedingly large series of numbers.

- The numbers shown on the thumb-tabs are each the cardinal nominative indicating 5 numerals or characters of the ordinal numbers of any one hundred subscribers within the particular one hundred desired; and in order to lessen by one-half the size of the book, each series of one hundred indicated 10 by any particular thumb-tab carrying its cardinal nominative, begins not on the front surface of such tabbed page, but on the back and opposing rear abutting surface of the immediately preceding sheet; and such one 15 hundred ends at the end of the indicating tab page with the last numeral of that particular hundred which is always 99. As an illustration, in a particular form of cardinal tab index shown in Fig. 1, the rear surface 20 of the untabbed first page (not shown) carries the ordinal numerals 1 to 49; while the opposed abutting surface of the second page carrying the thumb-tab marked 1, carries the ordinals from 50 to 99; all of which 25 ordinals are brought instantaneously to view upon thumbing the tab marked 1 and throwing the book open toward the left and rear so as to throw the untabbed first page back upon the front cover C.
- 30 The back surface of the sheet bearing the cardinal tab marked 1 begins with the ordinal numeral 100 (not shown) while the front opposing surface of the sheet carrying the cardinal tab marked "2" ends with 35 the ordinal character or numeral "199", while the back surface of said sheet begins with the ordinal character or numeral 200; and in like manner the back of sheet 29 with 3000; back of sheet 59 with 6000; the back 40 of 89 with 9000; and the page marked "119" ends with the ordinal character or numeral 11999; and the back surface of the first untabbed sheet of volume 2 of the book index (if any such there be) will begin with 45 the ordinal numeral 12000. Thus, the first volume of a multiple sectional book index so constructed and of my improved form, would in its 120 sheets contain and show 12000 ordinal numbers or characters, less 50 one; while all succeeding volumes of a like number of sheets would contain just an even 12000 of such numbers; but the number of sheets to a section, and the number of sections to a book or binder volume, may be 55 widely varied without departing from the spirit or scope of my invention.

And in like manner, the form of index may be somewhat varied; for it is evident that by having the first sheet (in this case 60 the untabbed front sheet) tabbed in blank or with a naught, the second sheet (now indicated by the cardinal tab 1, still being so marked) and an additional untabbed front page being placed in position to carry the 65 first half of the first one hundred ordinals,

that the same effect would be brought about, save that the back of the sheet marked "0" would begin with the ordinal "100."

The first section of leaves A, having tabs so numbered from 1 to 29 are perforated and 70 secured in the first binding bar 1, indicated by the numeral 4 in Figs. 1 and 2, by means of the securing-studs 11 and 12. The like secured second section of leaves A' bearing the cardinal numerals from 30 to 59 75 and carrying the individual numbers from 3000 to 5999, are in like manner inserted and secured in the second securing bar 4'. And it is self-evident from the drawing and description that the securing-bars 4 are vi- 80 bratorily secured in the back-piece by their hinged connections, such a distance apart that when the book is laid upon a table, and the backplate is rocked to the left of Fig. 1, to a horizontal or substantially horizontal 85 position, each section of the index leaves carried by each securing-bar 4 to 4' will be drawn back to the left just sufficiently far to uncover the index numbers of the like section lying immediately behind it, so that 90 when in such position every cardinal index number upon all of the indicating tabs of the entire index will be brought instantaneously to view; and it is also ap- 95 parent that by a single motion of the hand the book may be thrown back into position, so as to bring the backplate into a per- 100 pendicular position, and the book into the closed form shown in Figs. 6 and 7, when only the cardinal indicating tabs carried by the first section A will be on view, when the cover alone is lifted.

It is evident that different combinations of numerals, and other characters than numerals, in certain desired cases, may be used 105 in indexes of this character, with equal effect, as the particular series and combinations of cardinal and other indicating numbers shown; therefore, in my broad claims herein I have used the word character as 110 covering any and all characters of every kind and nature that may be so used for indexing, or other like purposes.

It is evident that when it is desired to insert or remove leaves in any inner section, 115 carried by any particular securing-bar, this can easily and quickly be accomplished by merely unscrewing and removing the studs 14, thereof, taking out the old leaf or leaves, and inserting the new leaf or leaves, when 120 such are necessary, and again screwing the studs in position.

It is evident from an inspection of the drawings, that in each of the three different forms of construction shown, the width from 125 front to rear of each of the several indexes individual to each of four several sections shown when brought to view upon the rock- 130 ing of the binder to the left and rear, will be substantially that of the distance between 130

the pivots or rock points of the several section-holding-bars of Figs. 1 to 6 inclusive, and of the thickness of the separating bars 29, 29¹ and 29², of the structure shown in 5 Fig. 7; being in each case that of the distance between the several sections at the point where they are secured at their rear edges to the back sheets of the binder; and such spacing apart of the sections at their rear and 10 securing edges, the width of the several sectional indexes to be simultaneously exposed to view by the rocking of the book and its opening at the required point, is of the essence, fundamental and crux of my invention, herein disclosed and claimed.

While the form in which I prefer to embody my invention is shown in Figs. 1 to 4 inclusive, there are many modifications of my invention which may be made without departing 20 from the scope thereof, and in Figs. 5 and 6 I have shown one modified form of construction of the device shown in said Figs. 1 to 4 inclusive, and in Figs. 7 and 8 another modification thereof. The device 25 shown in Figs. 5 and 6 differs only from that shown in the first mentioned Figs. 1 to 4, in that the securing-bars are made of two pieces of flat sheet metal, (the two together when in position forming the mechanical equivalent 30 of the one piece U shaped securing-bars 4 to 4³) and this particular form of bar I have designated by the reference letter D, numbering the bars from 4 to 4³, according to position, as in Figs. 1 to 3.

35 In this particular form of bar, the main plate 18 thereof is provided at the rearward end with the turned-up hollow coiled portion 19, by which the same is secured in position in the back-plate 1 by means of hinge-rods 40 5', which pass through upturned ends 8' of such back-plate 1, and are preferably riveted down at the ends. Coacting with such pivoted hinge-plate 18 is the secondary removable securing-plate 18'; these two plates 45 being held together and the section of leaves E to be bound between them being held in position by the screw-studs indicated by the numerals, 11 and 12, of substantially the same form as those heretofore described, and 50 shown in Fig. 2. In this particular construction, however, if desired, the hollow studs 14 may be soldered in position or otherwise rigidly secured to the pivoted plate 18; and when so constructed, upon the removal 55 of the screw 12, which will release the secondary removable bar 18', the leaves may be easily and quickly removed and replaced.

60 In operation this modified form of device differs in no particular from that hereinbefore described, as will be seen from a comparison of Figs. 1, 2, 3 and 4 with Figs. 5 and 6.

65 In Fig. 7 is shown another modified form of construction embodying the broad principle of, and differing but slightly from,

the constructions shown in Figs. 1 to 6 inclusive. In this particular form of binder, a backplate 20 of thin sheet steel, brass or other suitable metal, provided with the bottom L extension 21, having the upwardly extending screw-threaded stud-bolt 21' extending upwardly therefrom adjacent to either end thereof, upon each of which is screwed a hollow standard securing-stud or bolt 22, provided at the upper end with a female screw-thread adapted to receive a securing-screw 12', similar to the screws 12 of Figs. 1 to 6 inclusive, and, like them provided with a slot to receive a suitable driver. The L shaped backplate 20 and 21 is secured in any desired manner in the back of the flexible cover C, and is usually covered on the inside by a flexible covering of leather or other suitable fabric 24, sewed or otherwise secured to the back C² of the covers C and C¹, as shown in Fig. 7. Adjacent to the back portion C² at the rear of the flexible cover C of the binder, within the same, and usually covered by a suitable strip of leather or other suitable fabric 27 is a metallic stiffening-plate 28, which when in position is opposite to the L extension 21 of the back-plate 20.

90 The sections of leaves A to A³ when in position on the securing-studs 22, as shown in Fig. 7, are separated one from the other by bars 29, 29', and 29², which are usually in cross-section, of the rectangular form shown, which may be of wood or of hollow metal, as shown, or of any other suitable material, and their form may be widely modified without departing from the scope 95 of my invention. These bars extend longitudinally at the back of the binder, and are provided with perforations to receive the standards 22, as shown.

100 Fig. 8 is a view in detail of the binder-bar 30, consisting of a longitudinal flat bar 31 from which adjacent to the ends thereof depend the hollow securing-pins or sleeves 32, so spaced upon the binder-bar 31 as to 105 register with and pass down over the securing-studs 22, when in the binding position shown in Fig. 7.

110 In this form of the device, in order to bind the various sections of the index into book form, the bottom section A³ properly 115 perforated, is slipped down over the studs 22 into the position shown in Fig. 7, the first and bottom dividing bar 29², also provided with like perforations, is slipped down upon such securing-studs 22, the next section A² of the leaves of the index, placed in like manner in position upon such securing-studs, the second dividing-bar 29' also 120 slipped into position, and so on until the book is completed. When the last section A, (in this case, as shown in Fig. 7, the fourth counting from the bottom) is placed in position, the binder-bar 31 is placed in 125 position with the hollow securing sleeves 32 130

in registry with the securing-studs 22 and pushed down into position over the same. The back of the binder is then bent over so that the bar 30 will be over the bar 31, and 5 the securing-stud screws 12' are then from the outside of the binder passed through perforations provided therefor in such bar 31, and screwed fully home into the securing-studs 22, all as shown in Fig. 7, when all the 10 sections will be firmly secured together in the form of a bound book, upon the back of which being rocked to the left of Fig. 7, all the index-tabs of the various sections will be brought instantaneously to view, as hereinbefore described in referring to the particular modified constructions shown in the preceding Figs. 1 to 6.

It is evident that many modifications in the construction, combination and arrangement of the various parts of my said invention herein disclosed and described, other than those mentioned may be made without departing from the broad scope of my invention, and I do not intend to limit myself to the exact construction or constructions herein set forth.

While I have shown my invention herein as particularly applied to an index in the form of a bound-book, I do not intend 20 to limit myself to such particular construction, as the broad principle and essence thereof may be applied with equal facility to card indexes, etc., without in any manner departing from the scope thereof.

35 I claim:—

1. An index comprising a plurality of sections of leaves; a thumb-index for each of such sections dividing the same into individual sections; a binder securing all the sections together in such manner that when the binder is in the normal position, only the thumb-index cardinal characters of the first section will be visible, but so constructed that when the binder is rocked wholly toward one side all the cardinal index characters of the several sections will be brought 40 instantaneously into view; the several sections being spaced apart at the rear and securing edges, a distance substantially that of the width of the several indexes individual to each of the sections to be exposed to view upon such rocking movement.

2. An index comprising a plurality of sections, each composed of a plurality of leaves; a thumb-index for each of such sections dividing the same into individual sections; a binder securing all the sections together in such manner that when the binder is in the normal and closed position, only the thumb-index characters of the first section will be visible, but so constructed that when the binder is rocked wholly toward one side all the cardinal index characters of the several sections will be brought instantaneously into 55 view.

3. An index composed of a plurality of sections of leaves or sheets, each section comprising a plurality of leaves or sheets; each of such sections being provided with cardinal thumb-index indicating characters; and means for securing the leaves or sheets against displacement in such manner that upon the rocking wholly toward one side of all the sections, the cardinal indicating thumb-index characters of all the various sections will be brought instantaneously into view.

4. An index in the form of a bound-book, composed of a plurality of sections of leaves or sheets, each section comprising a plural- 80 ity of leaves or sheets; each of such sections being provided with cardinal thumb-index indicating characters; and means for securing the leaves against displacement in such manner that upon the rocking wholly toward one side of all the sections the cardinal indicating thumb-index characters of the various sections will be brought instantaneously into view. 85

5. An index in the form of a removable 90 loose-leaf bound-book, composed of a plurality of sections of leaves or sheets, each section being itself composed of a plurality of leaves or sheets; each of such sections being provided with cardinal thumb-index indicating characters; and means for securing the leaves or sheets against displacement in such manner that upon the rocking wholly toward one side of all the sections the cardinal indicating thumb-index numerals of 100 all the index sections will be brought instantaneously into view.

6. In a device of the class described, a back-plate; a plurality of securing-bars, each secured to the back-plate by a rocking 100 or hinged connection; means carried by the securing-bars for removably securing therein a plurality of leaves, and a flexible cover having a stiffening-bar secured thereto at the front edge, secured to the back-plate.

7. In an index, a back-plate having a plurality of hinged journal-portions, alternating with perforations adapted to receive co-acting hinge portions of vibrating members arranged in series longitudinal to such back-plate; and a plurality of vibrating members in the form of securing-bars, one for each line of the hinged journals, each adapted to receive a book section or signature composed of a plurality of leaves, and having 115 hinged-journals fitting into the perforations of the back-plate; and hinge-rods securing the vibrating members vibratory to the back-plate.

8. In a device of the class described, a 125 support; a plurality of spaced securing-bars; each vibratory pivoted in the support, and each adapted to receive a plurality of leaves in the form of a section or signature of leaves, each of such sections being 130

provided with a thumb-index, extending from top to bottom.

9. In a device of the class described, a plurality of spaced securing-bars, each 5 adapted to removably receive a plurality of leaves in the form of a section or signature of leaves, each of such sections being provided with a thumb index extending from top to bottom of such leaf sections.

10. 10. In a device of the class described, a plurality of spaced vibrating securing-bars, each adapted to receive a section composed of a plurality of leaves, and having a thumb-index individual to such section.

11. In a device of the class described, a plurality of spaced vibrating securing-bars, each adapted to removably receive a section composed of a plurality of leaves, and having a thumb-index individual to such 20 section.

12. In a device of the class described, a plurality of spaced vibrating securing-bars, each adapted to receive a section composed of a plurality of leaves, and having a thumb-index individual to each of such sections; and screws for securing the sections of leaves in their individual vibrating securing-bars.

13. In a device of the class described, a 30 back-plate; a plurality of spaced securing-bars, each adapted to have secured thereto a plurality of leaves, vibratorily supported longitudinally of the back-plate; each of which leaf sections carried by each securing-bar is provided with an individual thumb-index.

14. In a device of the class described, a back-plate; a plurality of spaced securing-bars, each adapted to have secured thereto a 40 plurality of leaves, vibratorily supported longitudinally of the back-plate; each of which leaf-sections carried by each securing-bar is provided with an individual thumb-index, having one character to each leaf of 45 such section.

15. In a device of the class described, a back-plate; a plurality of vibrating securing-bars arranged longitudinally of the back-plate spaced from one another and having a single pivot-point; a leaf-section carried by each of such vibrating securing-bars; and a thumb-index individual thereto carried by each of such leaf sections.

16. In a device of the class described; a

binder-portion having a back, a front and a 55 rear cover; a plurality of sections of leaves; means for securing such sections of leaves within the binder-portion adjacent to the back with spaces between each section of leaves; and a thumb-index upon the outer 60 edge of each section of leaves individual thereto; the width of the indexes, and the width of the spaces between the sections, being such, that when the binder portion is rocked wholly to one side every character of 65 all the indexes will be brought instantaneously to view.

17. An index composed of a plurality of sections, each made up of a plurality of leaves; a supporting back-piece; means for 70 securing each of such sections to the back-piece, so as to leave a space between the several sections adjacent to said back-piece; a thumb-index for each section at the free edge thereof, composed of a thumb-tab for each 75 leaf of the section, carrying a cardinal index character forming the nominative of the index ordinals set forth and beginning on the opposing abutting rear side or surface of the immediately adjacent front preceding 80 leaf, and on its front surface; the cardinal character of all the thumb-tabs of the several sections together forming a multiple-thumb-index; all of which indexes, save that carried by the first and front section will 85 be concealed from view when the book formed of the several sections is closed; the construction and arrangement being such that upon rocking the book composed of the sections so as to incline the back-piece to 90 toward the rear, all of the several indexes individual to the several sections will be brought instantaneously to view; whereupon, on thumbing any required cardinal thumb-tab and throwing the book open 95 thereat in the same direction; the two pages of ordinals of which such cardinal character is the nominative will also be brought instantaneously to view.

Signed at the borough of Manhattan, city, 100 county and State of New York, this ninth day of January, nineteen hundred and thirteen.

HUGH GELLROY BUCHAN.
